UNITED STATES PATENT OFFICE

JULIAN A. CAMPBELL, OF LONG BEACH, CALIFORNIA

METHOD OF ABSORPTION

Original applications Serial No. 46,974, filed July 30, 1925, and Serial No. 79,073, filed January 4, 1926.
 Divided and this application filed April 19, 1927. Serial No. 184,870.

This application is divisional of my application Serial Number 46,974, filed July 30, 1925, entitled "Absorber," now Patent No. 1,654,785, issued Jan. 3, 1928, and a division 5 of my application Serial No. 79,073, filed January 4, 1926, on "Absorber," and since issued, Sept. 27, 1927, No. 1,643,696. In this application the subject matter of the invention relates to a method for causing certain 10 relative flow and inter-contact of gases and liquids; leaving in said prior application Serial No. 46,974, the claims upon the structural features having relation to support, assembly, etc. For that reason the feature 15 relating purely to structure will not be described in detail in this application.

This invention has to do with methods of the general character variously known as absorption methods or systems; the purpose 20 of such methods being to intimately distribute and admix a gas or vapor with a liquid, so as to get intimate finely divided contact between the gas and liquid. Sometimes these methods are used for the purpose 25 of loading a gas or vapor with substances that they may pick up from the liquid by reason of their intimate contact therewith. Thus although the present method is termed 30 an absorption method and has been developed more particularly for use as such, and particularly for absorbing the vapors of volatile hydrocarbons such as gasoline from 35 casing head gas and the like, it will be understood that the invention is not thereby limited to such use. A description of an illustrative apparatus and its operation for carrying out the invention specifically as a method of 40 absorption will make it plain to all those skilled in the art how the method may be used for other purposes.

Although the general structure and details of apparatus hereinafter particularly described are but illustrative and indicative of a typical apparatus for carrying out the method embodying the invention, I give a 45 detailed and specific description of the preferred and specific form of device shown in the accompanying drawings so that others may have a full understanding of the invention; it not being intended that the method

be limited to use in the particular apparatus hereinafter described. For the purpose of such description, I now refer to the accompanying drawings, in which:

Fig. 1 is an exterior elevation, parts being 55 broken away, showing a form of my improved absorber;

Fig. 2 is an enlarged horizontal section on line 2—2 of Fig. 1;

Fig. 3 is an enlarged horizontal section on 60 line 3—3 of Fig. 1;

Fig. 4 is an enlarged vertical section of the lower part of the absorber showing the relative arrangements of its various elements; and

Fig. 5 is an enlargement in detail of certain portions of Fig. 4.

The absorber is preferably housed within a tower-like shell or casing 10 constructed of any suitable material, preferably of sheet or 70 plate metal. Within this tower there is a number of superimposed perforated floors 11. Each of these floors is formed of a suitable plate perforated with a large number of comparatively small openings, so that the 75 gas flowing up through the floors is broken up into fine streams. And these openings are of such a size that gas pressure beneath the floor will prevent flow of liquid downwardly through the perforations. 80

The structure for supporting these floors and for making fluid-tight joints between them and shell 10 is the particular subject matter of my issued Patent No. 1,654,785 and, therefore, will not be described here; 85 except that I say that, as indicated at 12, means are provided at the periphery of each floor for making a fluid-tight joint with the shell, and that the floors are supported on suitable columns or posts 13 that extend 90 vertically through the several floors. It will suffice here to say that the several floors are rigidly supported in vertically spaced relation, are supported so as to be accurately level and so that the overflow pans attached to 95 each floor are accurately in level.

Each floor, as I have said, is formed of a perforated plate; and each floor carries a plurality of overflow pans 30 supported on tubes 31 that pass through the floor and ex- 100

tend to a point near the floor next below. Pans 30 are carried at a suitable height above their corresponding floors, the height depending somewhat upon various conditions, including the character or consistency of the absorbing liquid. It is the function of these pans to take overflow from the froth that forms over each floor, and their height may be somewhat varied in order to make them properly perform their functions. Tubes 31 may be supported in floors 11 by flange connections 32; and at their lower ends these tubes have spreader cones 33 that lie close to the floor below; the lower ends of the tubes being at points near enough the floor below that they are always submerged by the liquid or liquid and froth on that floor. The column of liquids in the tubes during operation prevents passage of gas directly up through the tubes.

The tubes 31 of pans 30 associated with the lowermost floor 11, instead of having spreaders, have on their lower ends cups 34 forming liquid traps through which the gas cannot pass upwardly. By reference to Figs. 2 and 3 it will be seen that each floor carries a plurality of overflow pans 30 and that the arrangement on alternating floors is made so that the lower ends of tubes 31 from the floor 30 above are spaced between the pans 30 on the next floor below. The pans 30 are made of considerable area, and are preferably relatively shallow.

The absorbing liquid—in a typical case, a fairly heavy petroleum oil—is fed into the apparatus through pipe 35 and is distributed to the uppermost floor 11 by a perforated pipe 36. Flowing over this uppermost floor the liquid is prevented from flowing directly through the floor perforations by reason of the gas pressure beneath the floor. The gas is initially introduced at 37 below the lowermost floor 11 and at a point above the liquid outlet 38, so that gas is introduced above the liquid level standing in the bottom of the shell. The gas, under suitable pressure, passes upwardly through the perforations in the lowermost floor and bubbling up in finely divided streams, and therefore in fine bubbles through the liquid on that floor, creates a considerable froth which stands on the surface of whatever clear liquid there may be present. This froth is constantly breaking up and releasing the gas into the space above, the gas being thus released to pass under pressure through the next floor up. At each floor the same kind of action takes place until the gas passes through the uppermost floor, when it finally passes off through the gas outlet 39.

At each floor a mass of froth is formed; fine bubbles being formed by formation of a film of oil around each minute gas bubble. This finely divided froth blows up in each floor until it reaches the level of the upper edges of pans 30; and the uppermost part of

the froth then overflows constantly into the pans. It is the uppermost parts of the froth in which the individual bubbles are breaking and releasing gas; therefore the froth in this uppermost part, which flows over the edges of the pans and into the pans, breaks up, releases the entrained gas, and, in the form of clear liquid, flows from the pans through tubes 31 and thus down onto the next floor. As I have said before, the lower ends of tubes 31 are close enough to the next floor and submerged in the froth, and hold a column of liquid so that the gas cannot flow upwardly through the tubes. The gas is thus constantly being bubbled in very fine division through the liquid at each floor, a fine froth is constantly being formed, giving extremely intimate contact between the liquid and gas or vapor, the froth is constantly breaking up and the resultant liquid from the broken up froth is constantly flowing from one floor to the next. While the liquid is thus slowly flowing downwardly through the apparatus the gas is passing upwardly through it.

The capacity of the apparatus is governed mainly by its area in plan; the length of time during which the gas or vapor is in intimate contact with the liquid—and therefore the thoroughness with which absorption or other interchange between the gas and liquid takes place—is governed at least in part by the number of superimposed floors in the apparatus. However, it will be understood that in a structure of given size, the gas or vapor is in my apparatus put into much more intimate contact and kept in that contact during a much longer time period than is true in ordinary forms of absorption apparatus.

There are several features to which I wish particularly to call attention, these features having to do with the high efficiency obtained in my absorber. Considering Fig. 5, the froth level is there shown at L, this level being usually slightly above the peripheral edges of pans 30. I have found that a most effective breaking up of the froth and flow of comparatively clear liquid over the pan edges is obtained when the pan edges are left in what is known as the "raw" state. These pans are, in practice, made by cutting or shearing a strip of comparatively thin sheet metal (about #16 gauge), bending that strip to circular form and securing its ends together to form a side wall, and then securing the circular side wall to a bottom plate. In thus making the pans I leave the upper peripheral edge 30^a in its raw cut state, not smoothing it in any manner, as for instance by rolling or by smoothing off the edge. This sharp raw edge I find to be very effective in breaking up the froth at the pan edge; so that practically nothing but clear liquid flows into each pan and thus flows down through tube 31 to the next level.

When this liquid reaches the next level it is spread out over the next floor 11 by the spreader cones 33. It will be noted that these spreader cones are so placed and formed that they throw the liquid outwardly and cause it to move outwardly over the floor 11; and immediately upon striking the floor this liquid begins to be picked up by the gas that flows through the perforations, being thus intimately intermingled with the gas and again formed into froth. Spreading cone 33 spreads the liquid flow out into a comparatively thin sheet or film; and this fact tends to increase the intimacy of contact between the gas and liquid. But it will be noted that the liquid flowing down through tubes 31 and spread by cones 33 is not thereby thrown upwardly, but is only thrown outwardly; that its flow motion is only outwardly over the floor under the mass of froth and that, in order to move upwardly, this liquid must be picked up by the upwardly flowing gas and therefore can only be moved upwardly as froth. The froth is therefore initially formed where the liquid and gas meet at the lowermost part of the froth body; the froth body is constantly added to below and the froth is constantly moving up; and is likewise constantly being broken up at its upper surface. Furthermore it will be noted that, because pans 30 cover a substantial proportion of each floor area, and because the spreader cones are spaced between the pans, the tendency of the spreader cones is to throw the liquid horizontally outwardly under the pans. This is clearly indicated by the arrows in Fig. 5. Consequently the liquid that is picked up and moved upwardly by the upwardly flowing gas cannot, even if moved upwardly in fairly large bodies of liquid rather than as froth films, immediately reach a position where it could flow over the edge of a pan. It must, as indicated by the dotted-line arrows in Fig. 5, follow a more or less tortuous upward path to reach the liquid surface surrounding the pans; and in following such tortuous path it is, of course, at all times coming into contact with gas that is moving up through or with the body of froth. The gas that comes up under the pans must also follow a long tortuous path to reach the froth surface, thus increasing its contact with the liquid. And the spreading of the gas under the spreader cones has also the same effect.

The sum-total result of these arrangements is that a very high efficiency of action is obtained in my absorber, that action being due to the necessarily intimate contact between the gas and liquid and also due in some measure to the fact that, when the liquid flows from one level to the next, it is necessarily freed of gas.

At the lower ends of the lowermost tubes 31 it is not necessary to employ spreader cones, but the liquid seal cups 34 are there used merely to prevent gas from passing upwardly through the lowermost tubes 31. And it may

be noted in this connection that cones 33, which are made of hollow sheet metal, as is indicated in Fig. 5, protect the lower ends of tubes 31 and prevent gas from flowing directly upwardly from the perforated floor through the tubes. The gas that flows through the floor perforations directly below a cone 33 cannot flow directly up through the tubes, but is turned horizontally under the cone, flowing out under its lower edge, and this outward radial flow of gas under and around each cone helps in flowing the clear liquid radially outwardly over the floor around each cone, this aiding in a widespread of the liquid flow, thus decreasing so the thickness of liquid film and increasing the intimacy of contact between the upwardly flowing gas and the liquid. This outward radial flow of gas increases the length of its path to reach the froth surface; causes meeting and turbulence between the radial gas and liquid flows from adjacent cones; and increases both the time period and the intimacy of contact between gas and liquid.

I claim:

In a process of treating gases or vapors by contact with liquid, continuously forming and maintaining a homogeneous body of froth in which the liquid is substantially wholly in the form of film surrounding bubbles of gas or vapor, the froth being continuously formed by introduction of both liquid and gas or vapor in intimate contact at the lower part of the froth body thus building up the froth body from its lower part, and continuously breaking up the froth and liberating the gas or vapor at the upper surface of the froth body at the same rate at which the froth is formed.

In witness that I claim the foregoing I have hereunto subscribed my name this 9th day of April, 1927.

JULIAN A. CAMPBELL.
